Attorney.

UNITED STATES PATENT OFFICE.

MAX CARL AUGUST HERMANN PAPE, OF NEUMUHLEN-DIETRICHSDORF, NEAR KIEL, GERMANY, ASSIGNOR TO THE FIRM CARBONIT-AKTIENGESELLSCHAFT, OF HAMBURG, GERMANY.

SEA MINE.

Application filed September 30, 1920. Serial No. 413,881.

(GRANTED UNDER THE PROVISIONS OF THE ACT OF MARCH 3, 1921, 41 STAT. L., 1313.)

To all whom it may concern:

Be it known that I, MAX CARL AUGUST HERMANN PAPE, a citizen of the German Republic, residing at Neumuhlen-Dietrichsdorf, near Kiel, Germany, have invented certain new and useful Improvements in Sea Mines (for which I have filed application in Germany, Oct. 22, 1913, Patent Number 298,562; Russia, May 9, 1914; Austria, 10 Feb. 15, 1917; Hungary, Feb. 16, 1917; Sweden, Dec. 4, 1919; Finland, Dec. 11, 1919; Spain, Dec. 6, 1919; Czechoslovakia, Feb. 17, 1920), of which the following is a specification.

15 This invention relates to sea mines of that type in which the vessel is oblong or fish-shaped so that it adjusts its head in the direction of the current. Mines of this type present, in comparison with the pear-shaped or spherical mines, the advantage that they 20 oppose much less resistance to the water than mines of the latter types.

This advantage is however more or less lost owing to the fact that the mines when 25 submerged adopt a more or less inclined position according to the current and to the angle of inclination of the anchor cable, the mine presenting thus a much larger surface of attack for the current, said surface of 30 attack corresponding with the projection upon a plane which stands vertical to the direction of the current.

In order to prevent the inclined position 35 of the mine it has been proposed to arrange the anchor cable so that it is attached to the mine in front of the middle of its length, rigid steering fins being arranged at the rear end of the mine.

It has however been shown, that owing to 40 these rigid fins designed to maintain the horizontal position of the mine considerable resistance is opposed to the water wherefrom results that mines of this type are undershot more than mines without such fins.

45 This invention has for its purpose to do away with these steering fins and to ensure the horizontal position of the mine in a simple but reliable manner through placing the center of gravity of the mine so far behind the middle of its length that a turning moment is produced which effects a horizontal adjusting of the mine in the direc-

tion of the longitudinal axis through the buoyancy of the mine when the same is being anchored.

55 The invention is illustrated in the accompanying drawings, in which—

Fig. 1 is a side elevational view of the mine illustrating the position which it assumes when floating.

60 Fig. 2 illustrates the position of the mine when it is submerged.

The mine vessel is designated by the reference numeral 1 and it is provided at its rear end with fins 2 for steering in a horizontal direction. It is seen that the mine vessel is oblong and the addition of the fins gives it the general shape of a fish. Towards its front the mine vessel has attached thereto a hook 3 or a similar device to which 70 anchoring cable 4 may be attached.

65 In this mine of improved construction the centre of gravity of the mine is displaced, through correspondingly distributing the weight, so far towards the rear end that the longitudinal axis of the mine adopts in the floating position upon the surface of the water a position which is inclined with regard to said surface (Fig. 1), the point at 75 which the cable is attached being situated in proximity of the head.

In considering the buoyancy of the mine and the position of the centre of gravity of the same the position of the point at which the anchor cable is attached has been determined through simple calculation or by tests so that the mine adopts under water an exactly horizontal position (Fig. 2), as the turning moment produced by the holding force of the cable has been made so great 90 that the mine when submerging is turned for the same angle for which its longitudinal axis deviates from the horizontal when the mine is in the floating position upon the surface of the water.

95 A mine of this construction opposes constantly the smallest resistance against the current and remains perfectly balanced and at rest even in a very strong current. The fins shown serve merely for steering in horizontal direction and may be suppressed.

100 I claim:—

1. A sea mine of the class described, comprising an oblong mine vessel in which the

load is so distributed that the center of gravity is rearward of the center of the longitudinal axis of the vessel so that the mine when floating tends to assume a position such that its longitudinal axis is inclined in a vertical plane, and means carried by the end of said vessel, which is forward of the center of its longitudinal axis, to which an anchoring cable can be attached, said means being so located with respect to the center of gravity of the mine that the drag of the anchoring cable causes the mine when submerged to assume a position with its longitudinal axis substantially horizontal.

2. A sea mine of the class described, comprising an oblong fish-shaped mine vessel in which the load is so distributed that the center of gravity is rearward of the center of the longitudinal axis of the vessel so that the mine when floating tends to assume a position such that its longitudinal axis is inclined in a vertical plane, and means carried by said vessel forwardly of the center of its longitudinal axis to which an anchoring cable can be attached, said means being so located with respect to the center of gravity of the mine that the drag of the anchoring cable causes the mine when submerged

to assume a position with its longitudinal axis substantially horizontal.

3. A sea mine of the class described, comprising an oblong mine vessel having a central substantially cylindrical portion, a substantially cone-shaped rear end and a substantially semi-spherical front end, the load in said vessel being so distributed that the center of gravity is rearward of the center of the longitudinal axis of the vessel so that the mine when floating tends to assume a position such that its longitudinal axis is inclined in a vertical plane, and means carried by said vessel forwardly of the center of its longitudinal axis to which an anchoring cable can be attached, said means being so located with respect to the center of gravity of the mine that the drag of the anchoring cable causes the mine when submerged to assume a position with its longitudinal axis substantially horizontal.

In testimony whereof I affix my signature in presence of two witnesses.

MAX CARL AUGUST HERMANN PAPE.
